US0D1068267S

(12) **United States Design Patent** (10) **Patent No.:** **US D1,068,267 S**
(45) **Date of Patent:** **** Apr. 1, 2025**

(54) **TOOL STORAGE CASE**

(71) Applicant: **SHENZHEN FANTTIK TECHNOLOGY INNOVATION CO., LTD**, Shenzhen (CN)

(72) Inventor: **Zhiqiang Liang**, Shenzhen (CN)

(73) Assignee: **SHENZHEN FANTTIK TECHNOLOGY INNOVATION CO., LTD.**, Shenzhen (CN)

(**) Term: **15 Years**

(21) Appl. No.: **29/901,810**

(22) Filed: **Sep. 6, 2023**

(51) LOC (15) Cl. **03-01**

(52) U.S. Cl. **D3/294**
USPC ....

(57) **CLAIM**

The ornamental design for a tool storage case as shown and described.

DESCRIPTION

FIG. 1 is a first perspective view of a tool storage case showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the tool storage case where the tool storage case is in a closed state;

FIG. 10 is an enlarged view of an encircle portion 10 in FIG. 1;

FIG. 11 is an enlarged view of an encircle portion 11 in FIG. 2;

FIG. 12 is an enlarged view of an encircle portion 12 in FIG. 5; and,

FIG. 13 is an enlarged view of an encircle portion 13 in FIG. 8.

The broken lines in the Figures are for the purpose of illustrating portions of the article that form no part of the claimed design.

The dash-broken lines encircling portions of the claimed design that are illustrated in enlargements form no part of the claimed design.

1 Claim, 13 Drawing Sheets
